Primary Examiner — Manpreet Matharu*Assistant Examiner* — Aula Soroush(74) Attorney, Agent, or Firm — Troutman Sanders LLP; Tory Kleckley; Alexis Simpson(57) CLAIM

The ornamental design for a play cape with high collar, as shown and described.

DESCRIPTION

FIG. 1 is a perspective view of a play cape with high collar showing my new design in a worn state;

FIG. 2 is a front elevation view thereof;

FIG. 3 is a back elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines showing a human form illustrate environmental subject matter and form no part of the claimed design.
